US0D1072591S

(12) **United States Design Patent** (10) **Patent No.:** **US D1,072,591 S**
(45) **Date of Patent:** **** Apr. 29, 2025**

(54) **RATCHET WRENCH**

(71) Applicant: **HONG ANN TOOL INDUSTRIES CO., LTD.**, Taichung (TW)

(72) Inventor: **Cheng-Wei Su**, Taichung (TW)

(73) Assignee: **HONG ANN TOOL INDUSTRIES CO., LTD.**, Taichung (TW)

(**) Term: **15 Years**

(21) Appl. No.: **29/876,620**

(22) Filed: **May 25, 2023**

(51) LOC (15) Cl. **08-05**

(52) U.S. Cl.

USPC **D8/21**; D8/25

(58) **Field of Classification Search**

USPC D8/24, 107, 21, 22, 25; D10/83

CPC B25B 23/1425

See application file for complete search history.

Assistant Examiner — Benjamin D. Wannemacher

(74) Attorney, Agent, or Firm — Muncy, Geissler, Olds & Lowe, P.C.

(57) **CLAIM**

The ornamental design for a ratchet wrench as shown and described.

DESCRIPTION

FIG. 1 is a perspective view of a ratchet wrench showing my new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken lines depict portions of the ratchet wrench that form no part of the claimed design.

1 Claim, 7 Drawing Sheets
